UNITED STATES PATENT OFFICE

ARTHUR W. NICHOLS, OF NEW YORK, N. Y.

SOUNDING DEVICE

Application filed October 23, 1928. Serial No. 314,353.

This invention relates to new and useful improvements in sounding devices adapted for use by orchestras within theatres, dance halls and the like, and in order that the sound 5 of rifle, rapid fire guns, or running or trotting horses may be simulated. An important object of the invention is to provide a device of this character that is extremely simple in construction and inexpensive of manufacture, and highly well adapted for the purposes intended.

With the foregoing and other objects in view as the nature of the invention will be better understood the same comprises the 15 novel form, combination and arrangement of parts hereinafter more fully described, shown in the accompanying drawings and claimed.

In the accompanying drawings wherein like reference characters indicate corresponding parts throughout the same:

Figure 1 is a front elevation of my improved sounding device.

Figure 2 is a view mainly in side elevation, and partially in cross section.

Figure 3 is a detail horizontal section taken substantially upon the line 3—3 of Figure 1 and looking downwardly in the direction of the arrows.

Figure 4 is a similar view taken substantially on the line 4—4 of Figure 1.

Figure 5 is a perspective of one of the finger operating cams.

Now having particular reference to the drawings, my novel invention consists of 35 a backing plate or board 5 associated with the upper end of which is a suitable casing 6. Arranged longitudinally within this casing is a shaft 7 equipped at predetermined spaced points with suitable cams 8. One end of the 40 shaft 7 is equipped with a crank handle 9 whereby to facilitate the rapid rotation of said shaft. Beneath this shaft casing 6 the front surface of the backing board 5 is equipped with suitable supporting means 10 45 while arranged upon the forward ends there-

of is a board 11, the outer face of which is provided with a pad 12 of predetermined thickness of material and softness. The shaft housing 6 is open for the greater portion of its bottom area and pivoted to the 50 housing directly beneath the shaft are depending striker fingers 13 that project upwardly into the housing and terminate within the surface of the respective cams so that when the cams rotate, the inner ends of these 55 fingers will be engaged to cause the outward movement of the lower ends thereof with respect to the pad 12. Between each finger 13 and the backing plate of the device are retractile coil springs 14 for the purpose of 60 normally maintaining the lower flat ends of the fingers for engagement with the pad 12, and the upper ends thereof in engagement with said cams 8. Obviously therefore the rotation of the shaft 7 will cause the rotation 65 of said cams and by reason of the staggered relation of the projections of the cams with respect to each other, the fingers will be caused to alternately strike the pad 12 for simulating the sound of a rifle, a rapid fire 70 gun or the hoof beats of animals.

In view of the foregoing description when considered in conjunction with the accompanying drawings it will be apparent that I have provided a novel, simple and highly 75 useful sounding device that is well adapted for all the purposes heretofore designated.

Even though I have herein shown and described the invention as consisting of certain detail structural elements it is nevertheless 80 to be understood that some changes may be made therein without affecting the spirit and scope of the appended claim.

Having thus described the invention, what I claim as new and desire to secure by Letters Patent is:

A sound producing device comprising a base, a hollow casing supported on one end of the base, a shaft extending through the casing and journaled through the opposed 90

walls thereof, said shaft having a crank handle coupled to one end of the shaft, a plurality of cams secured to the shaft at spaced points along its axis, said casing having an opening in one wall, a plurality of flat striking fingers pivoted intermediate their ends to the casing and having one end of each finger extending through the opening and terminating in the path of the cams, a striking pad supported in spaced relation to the other end of the base adjacent the free ends of the striking fingers and springs secured to the base and the fingers to normally urge the fingers to contact with the base.

15 In testimony whereof I affix my signature.
ARTHUR W. NICHOLS.
